UNITED STATES PATENT OFFICE.

WILLIAM R. KINNEAR, OF NEW YORK, N.Y.

RADIATOR.

No. 815,354.

Specification of Letters Patent.

Patented March 20, 1906.

Application filed November 4, 1904. Serial No. 281,504.

To all whom it may concern:

Be it known that I, WILLIAM R. KINNEAR, a citizen of the United States, residing at New York, in the county of New York, in the State of New York, have invented certain new and useful Improvements in Radiators, of which the following is a specification.

This invention relates to radiators, and it has for an object to provide an improved radiator that is in the form of a heater—that is, that carries its own generator.

It has for further objects to improve the construction of the generator and to provide an improved means for securing the radiating units to a chamber, such as the generator that connects all of the units.

Other objects and advantages will appear in the following description and will be more particularly pointed out in the claims.

20 In the drawings, Figure 1 is a front elevation, partly in section, of one embodiment of my invention. Fig. 2 is a vertical section on the line 2 2, Fig. 1. Fig. 3 is a horizontal section on the line 3 3, Fig. 1. Fig. 4 is a detail view of the sleeve used in the embodiment shown in Fig. 1 to secure the lower ends of the radiating units to the generator. Fig. 5 is a vertical section of the top of the generator unit on the line 5 5, Fig. 3; and Fig. 6 is a 25 side view of one of the legs employed in the embodiment shown in Figs. 1 to 5. Fig. 7 is a vertical longitudinal section of one end of another embodiment of my invention. Fig. 8 is a transverse section on the line 8 8, Fig. 7.

30 Referring more particularly to the drawings, 9 indicates the radiating units connected together at their sides near their upper ends by open bosses 10 and at their lower ends by a chamber or generator 11. The top 15 of the chamber 11 is formed with openings 12, corresponding in number to the number of radiating units and conforming in shape to the cross of the lower ends of said units. Connecting-sleeves 13 are fitted in the openings 12 and the lower ends of the radiating units, said sleeves conforming to the shape and size of the inner walls of the lower ends of the units with which they engage and being provided with outwardly-extending rims or 45 flanges 14, which engage with the top 15 around the openings 12.

The front, rear, and bottom walls of the generator 11 are formed out of a single sheet of metal bent to provide an upper enlarged

portion 11' and a reduced lower portion 11², 55 having a forwardly-inclined front wall 11³ provided with an asbestos covering 11⁴. The end walls of the generator are formed by a pair of cast-metal legs 16, which are held against the edges of the top, bottom, front, 60 and rear walls by means of tie-rods 17. These legs are provided with sockets 26, in which the ends of a burner 27 seat. One end wall is provided with openings 28 and 29, into one of which is threaded an upwardly-turned 65 pipe which serves for supply-water to the generator and into the other of which is fitted a pipe for attaching a gas hose or pipe to supply the burner 29.

To securely hold the chamber 11 to the radiating units, a bar 18 is provided which extends within the chamber 11 beneath all of the openings 12 and engages with all of the lower ends of the connecting-sleeves 13. This bar 18 is firmly held in place by hangers 70 or tie-rods 19 and adjusted by means of nuts 20 on said hangers. The hangers or tie-rods 19 are mounted inside of the units and are anchored at their upper ends by eyelets 21, connecting opposed walls of the units, the 80 eyelets being strengthened and the units being at the same time held together by a rod 22, which extends through aligned eyelets of the units.

In the embodiment shown in Figs. 1 to 6 85 the radiating units 9 rest upon the top 15 around the opening 12, the top is provided with ribs 15^a, struck up from the metal of the top and bearing against the outside walls of the units to prevent the expansion of the 90 units at this point, and the flanges 14 on the sleeves 5 are flat. Further, the top 15 is connected by seams 15^b and 15^c on the front and rear edges of the top with the upper edges of the sheet of metal which forms the front, 95 rear, and bottom walls of the chamber 11. The bar 18 consists of a thick iron strip, while the end walls or legs 16 are formed with grooves 16^a, which conform to the cross-section of the chamber 11. (See Fig. 6.)

In the embodiment shown in Figs. 7 and 8 the opposed walls of the units 9 are connected together by thimbles 22^a at a point slightly above their lower ends, this connection being provided to prevent the expansion of the 105 walls so as to break the joint between the radiating unit and the chamber 11. The top 15 instead of being provided with ribs 15^a, is

provided with depending flange 15^d and the ends of the units 9 bear against the inner walls of the flanges. The flanges 14 are provided with upwardly-turned ends 14^b, which form troughs in which the ends of the units 9 and the flanges 15^d fit. The top 15 is formed from the same sheet of metal that forms the front, rear, and bottom walls of the chamber 11, the two edges of the sheet of metal being united at the rear by turning the upper edge rearwardly and upwardly to form a trough 15^e and the lower edge downwardly to rest in the trough, as at 15^f. The walls of the lower portion 11^g of the chamber 11 are tied against expansion by a thimble 23, bearing against opposite walls, and a rivet 24, passing through the thimble. The bar 18 consists of a sheet of sheet metal having its edges bent upwardly at 18^a and then downwardly at 18^b to strengthen the same. The end walls or legs 16 are formed with flanges 16^b, which contact with the outer wall of the chamber 11, while plates 16^c, secured by bolts 16^d, engage the inner wall to grip the edges of the sheet of metal. The troughs formed at the joint between the units and the chamber 11 and at the joint at the rear wall of the chamber 11 serve to trap a portion of zinc, into which the radiator is dipped after being assembled. If at any time the radiator should become so hot as to melt the zinc, the troughs will prevent it from running from the joints.

The embodiments herein shown and described are for the purpose of illustration only, and it is to be understood that I may make within the scope of the appended claims various changes without departing from the spirit or sacrificing any of the advantages of my invention.

Having described my invention, what I claim is—

1. In a radiator-heater, the combination with a plurality of alined radiating units, of a generator having its bottom, top, front and rear walls formed of sheet metal into an upper chamber, opening at its top into the lower ends of all the units and an elongated lower reduced portion, cast-metal end walls for the generator, having legs formed thereon, and tie-rods connecting the cast-metal end walls.

2. In a radiator, the combination with a plurality of units, of a chamber connecting the units, a bar within the chamber, and tie-rods within the units and secured to the bar to hold the units and the chamber together.

3. In a radiator, the combination with the units, of a chamber, flanged sleeves connecting the units and the chamber, a bar fitted within the chamber, tie-rods fitted within the units and holding the units and chamber together.

4. In a radiator, the combination with the units, of a chamber, sleeves provided with troughed flanges and connecting the units

and chamber, a bar positioned within the chamber and bearing against the sleeves, and tie-rods positioned within the units and engaging the bar.

5. In a radiator, the combination with a plurality of units, of a chamber connecting the units, means tying opposed walls of the units, and tie-rods supported within the units by said tying means.

6. In a radiator, the combination with a plurality of units, of a chamber connecting the units, thimbles connecting opposed walls of the units, tie-rods supported from the thimbles within the units, and a bar positioned within the chamber and having the tie-rods secured thereto.

7. In a radiator, the combination with a plurality of units, of a chamber, flanged sleeves fitted through the chamber and into the units, thimbles connecting opposed walls of the units, a bar positioned within the chamber and bearing against the sleeves, and tie-rods connecting the thimbles and the bar.

8. In a radiator, the combination with a chamber provided with openings, of inwardly-extending flanges surrounding the openings, radiating units fitted within the openings and bearing against the flanges, and sleeves provided with troughed flanges embracing the flanges on the chamber and the ends of the units.

9. In a radiator, the combination with a plurality of units, of a chamber connecting the ends of the units, thimbles struck up from opposed walls of the units, tie-rods extending through alined thimbles, a bar positioned within the chamber and tie-rods connecting the bar and the thimbles.

10. In a radiator-heater, the combination with the alined vertical radiating units, of a generating-chamber connected to the same and having the bottom, front and rear walls bent from a single sheet of metal to form an enlarged upper portion and a reduced elongated lower portion, and an asbestos covering for one of the walls of the reduced lower portion.

11. In a radiator-heater, the combination with the radiating units, of a generating-chamber positioned below and connected to the same and having its bottom, front and rear walls bent from a single sheet of metal to form an enlarged upper portion and a reduced lower portion and cast-metal legs forming the end walls of the generating-chamber.

12. In a radiator-heater, the combination with the radiating units, of a generating-chamber having its top, bottom, front and rear walls bent from a single sheet of metal to form an upper enlarged portion and a lower reduced portion, the edges of the metal being united by bending the upper edge upwardly to form a trough and the lower edge downwardly into the trough; cast-metal legs form-

ing the end walls of the chamber; and a burner playing upon the lower reduced portion of the generating-chamber.

13. In a radiator-heater the combination with the radiator units, of a generating-chamber having its top, bottom, front and rear walls bent from a single sheet of metal, the edges of the metal being united by bending the upper edge upwardly to form a trough

and the lower edge downwardly into the trough.

The foregoing specification signed this 17th day of August, 1904.

WILLIAM R. KINNEAR.
